SEAT FOR EQUALIZING BARS

Filed Oct. 3, 1928

By

INVENTOR
Ivar A. Randel
Gillmor, Marin Co. Calif.

UNITED STATES PATENT OFFICE.

IVAR A. RANDEL, OF CHICAGO, ILLINOIS, ASSIGNOR TO RALPH BROWN, OF CHICAGO, ILLINOIS.

SEAT FOR EQUALIZING BARS.

Application filed October 3, 1928. Serial No. 310,144.

The invention relates to trucks for railway cars and more particularly to seats for equalizer bars.

The principal object of the invention is the provision of interchangeable equalizer bar seats having new and improved means for maintaining the application of the fore and aft pressure on the pedestals at a substantially constant distance from the base of the pedestals.

Another object of the invention is the provision of a new and improved seat for equalizer bars that will permit a limited universal movement between said bars and seats.

A further object of the invention is the provision of an equalizer bar seat that is simple in construction, cheap to manufacture, easily applied, efficient in operation, and that is not likely to become broken or deranged while in use.

Other and further objects and advantages of the invention will appear from the following description taken in connection with the accompanying drawings in which

Fig. 1 is a longitudinal section of a portion of a railway truck showing the invention in position thereon with parts broken away;

Fig. 2 is a section on line 2—2 of Fig. 1 with parts broken away and parts omitted for the sake of clearness;

Fig. 3 is a section on line 3—3 of Fig. 2;

Fig. 4 is a top plan view of one of the equalizer bar seats; and

Fig. 5 is a top plan view of one of the journal boxes and associated parts, with parts in section and parts broken away.

Referring now to the drawing, the reference character 10 designates a railway car truck of the six wheel type having the usual wheel piece 11 to which are attached, what for convenience will be termed, the front, rear and intermediate pedestals 12, 13 and 14, respectively. There is a pedestal at each end of each journal box, see Fig. 5. Each pedestal comprises two depending arms 15 and 16

which are connected together at their lower ends by a tie bar 18, as is usual in such constructions.

Journal boxes 19, 20 and 21 are slidably mounted between the depending arms of the pedestals 12, 13 and 14, respectively. The car axles are shown more or less diagrammatically at 200, 22 and 23, and the bearings and wedges therefor are designated generally by the reference character 40.

The car 10 is resiliently supported from the axles by suitable equalizing bars 24 and 25. These bars are substantially U-shape and have their ends 26, 27 and 28, 29, respectively, extending in opposite directions and supported by the journal boxes. Springs 31 are interposed between the equalizing bars and the car frame and are so arranged that the load will be equally distributed among the three journal boxes.

Equalizer bar seats or blocks 32, 33 and 34 are provided for supporting the ends 26, 27, 28 and 29 of the equalizer bars from the journal boxes. The blocks 32 and 34 are provided with ribs 35 for engaging corresponding recesses in the outer ends of the equalizer bars to prevent longitudinal movement of said bars. The rib 36 of the central block 33 engages a groove formed in the meeting ends of the bars 24 and 25.

It is desirable that the car frames be supported at a uniform distance above the tracks in order that the platforms, couplers, brakes and the like be supported at a constant height above the rails, and the truck frame maintained in a horizontal position.

It is well known that the tread portions of some of the wheels wear faster than others which will result in the equalizer bars resting unevenly on their seats, thereby tending to tilt the journal boxes and considerably increasing the friction between the boxes and the pedestals or guides. It frequently happens that some of the wheels of a truck must be replaced. It is extremely difficult to

match the wheels and often the wheels supplied are of different diameters from those remaining on the truck, and as a result the ends of the equalizer bars are supported at 5 unequal distances from the rails.

The present invention seeks to remedy these difficulties by providing a plurality of interchangeable equalizer seats of varying thicknesses for compensating for the difference in diameters of the wheels.

Assuming that the tires of the wheels on the axles 200 are worn most, those on axle 22 next, and those on axle 23 the least, the equalizer seats will vary in thickness in the same 15 manner for compensating for this wear, that is, the seat 32 will be the thickest, the seat 33, next and the seat 34, the thinnest. By providing blocks of different thicknesses and properly utilizing the same as occasion 20 requires, the ends of the equalizer bars may be maintained at a substantially constant height above the tracks.

In order that the weight may be properly distributed on the journals even though there 25 may be tilting of the axles due to unevenness in the road bed and tracks; or tilting of the equalizer bars on account of the unequal wearing of the wheel treads, or the like, it is necessary to provide automatically adjustable 30 bearings for the equalizer bars. As shown, universal joints or bearings are provided between the equalizer seats and the journals. The journal boxes are each provided at its upper portion with a convex surface 340 in 35 the form of a segment of a sphere which is engaged by a corresponding concave surface or segmental spherical recess 350 on the lower portion of the cooperating equalizer seat. This joint between the equalizer seat and the 40 journal box is in the nature of a universal or ball and socket joint although the movement in the different directions is extremely limited.

When it becomes necessary to employ 45 comparatively thick equalizer seat blocks, in order to maintain the ends of the equalizer seats in a horizontal plane, the axles are supported so near the ends of the arms that the vibration, buffs, and jerks to which the car is 50 subjected in use will tend to spread the pedestal arms apart. In order to avoid this difficulty, suitable means are provided for maintaining the application of the fore and aft pressure at a substantially constant distance from the base of the pedestal.

Any suitable means may be employed for this purpose. In the form of the device selected to illustrate one embodiment of this invention, the equalizer bar blocks or seats are 55 provided with flanges on their ends for engaging the base of the pedestal arms, whereby the shocks tending to spread the arms will be applied to the same relative position on the pedestal arms irrespective of the thickness 65 of the equalizer bar seat.

In the form shown, which is by way of example only, each block is provided with depending flanges 37 and 38 at, what for convenience will be termed its front and rear ends. The journal boxes are provided with 70 upstanding flanges 41 and 42 between which the blocks engage. These flanges prevent the blocks from moving longitudinally of the journal box, that is, transversely of the truck. The body portion 43 of each block or seat is 75 provided with upstanding flanges 44 and 45 extending longitudinally thereof, see Fig. 4. These flanges are oppositely offset at their ends for forming the shoulders 46 and 47 and may if desired be continued to form the retaining flanges 48 and 49, respectively. 80

These shoulders and flanges are adapted to engage the arms of the pedestals whereby the force of the shocks of the car will be transmitted to the pedestals adjacent to the base of the arms. The height of the flanges above the seats does not vary for the different blocks, consequently the force of the shocks will be applied at a substantially constant height above the rails or at the same distance from the base of the arms, irrespective of the thickness of the block, whereby the tendency of the force of these shocks to spread the pedestal arms will be reduced to a minimum. 90

It is thought from the foregoing taken in connection with the accompanying drawings that the construction and operation of my device will be apparent to those skilled in the art, and that various changes in size, shape, proportion and details of construction may be made without departing from the spirit and scope of the appended claims. 100

I claim as my invention:

1. In a truck for railway cars, a journal box having a segmental spherical surface on its upper side, an equalizer bar seat having a corresponding recess for engaging said surface, said seat being provided with an upstanding projection thereon, and an equalizer bar having a recess for engaging said projection. 105

2. An equalizer bar seat comprising a body portion having a segmental spherical recess in its under side and having flanges on its front and rear portions, said flanges extending below said body portion. 115

3. An equalizer bar seat comprising a body portion having a journal box engaging surface and pedestal engaging flanges extending a substantial distance above said journal box engaging surface. 120

4. In combination, a railway truck comprising front, rear and intermediate wheels at one side of said truck, said wheels having tires of different thicknesses, a journal box for each wheel, an equalizing bar between the front and intermediate wheels and one between the rear and intermediate wheels, a removable seat for supporting the ends of said 125 130

bars, said seats being of different thicknesses to compensate for the difference in thickness of said tires, and a pedestal having depending arms at each side of said box, each of 5 said seats being provided with upstanding shoulders extending above said seat for engaging said arms adjacent the base thereof.

5. An equalizer bar seat having a segmental spherical recess on its under surface, 10 and upstanding shoulders extending a substantial distance above said seat for engaging the arms of a pedestal.

In testimony whereof I affix my signature.
